INDICATOR DEVICE

Application filed September 9, 1930. Serial No. 480,651.

This invention relates to an indicator device for use in artificial respiration producing apparatus of the type disclosed in a co-pending application to J. S. Waterman, filed 5 July 19, 1930, Serial No. 462,158. In that machine the patient is placed on an inclined base with his arm pits resting on movable supporting members. A reciprocating handle operating member is provided for 10 imparting movements to the movable supports and to a pair of bars disposed in lines parallel to the inclined surface of the base. These bars carry a belt arranged to secure 15 pads in close contact with the body of the patient, the arm pit supporting members and the belt being actuated in such a sequence of operation as to induce artificial respiration in the manner of the so-called Schaeffer method of resuscitation.

20 In such a machine, however, it is necessary that the handle operating member be actuated at a constant number of strokes per unit of time in order to secure the desired effect.

The object of this invention is to provide 25 a device which will indicate the rate of movement of the operating member of the machine in a simple and positive manner.

In accordance with this invention a pressure gauge of the Bourdon type is operated 30 by air pressure built up in an expansion chamber by the movement of a piston in a cylinder. This piston is actuated by the movement of the reciprocating handle member and a system of valves controls the pressure in the chamber, the gauge being graduated 35 in a manner to translate the pressure in the chamber in terms of the number of strokes of the handle per unit of time.

In the drawing, 40 Fig. 1 is a perspective assembly view of the artificial respiration producing machine showing the indicator mounted thereon;

Fig. 2 is a view of the indicator with a 45 number of operating parts in section and

Fig. 3 is another sectional view of the indicator.

In more detail the artificial respiration producing machine to which this indicator device may be used generally consists of a 50 base 10 having an inclined top surface pro-

vided with a pad or mattress 14 upon which the patient's chest is supported. A head rest 15 is adjustably mounted on brackets 17 and 18 which are in turn secured at the lower ends to the base 10. A pair of supporting 55 plates 19 and 20 fit the patient's arm pits and are hinged to the base 10. These plates are arranged to be actuated to and from each other by the movement of a hand operating member 26', through respective connecting 60 rods such as 24. The handle lever is pivoted to opposite sides of the base 10 on pivots 26, one of them being shown in Fig. 1. To the opposite sides of base 10 are pivotally mounted as at 39, the bell crank levers 40. 65 The ends of these levers are connected to the operating handle lever members as at 41 and to a pair of parallelly disposed movable bars 35 to which the belt portions 27 and 28 are attached and arranged to be secured in close 70 contact with the body of the patient. Each of these bars are pivoted at their other ends on links 38 in order to impart to the belt 27-28, during each stroke, movements in directions substantially at right angles to each 75 other, the combined actions of the supporting plates 19 and 20 and the belt 27-28 on the patient being better known as the Schaeffer method of resuscitation.

One of the bell-crank levers 40 is provided 80 with an arm 50 to which a rod 51 is connected. This rod carries a piston 52 arranged to be reciprocated in a cylinder 53 for pumping air in a pressure chamber 54 under control of a valve CO which consists 85 of a ball 68 and a spring 67 holding this ball against the seat of this valve. To chamber 54 is connected a gauge 55 through the medium of a pipe 56. The inlet valve IN 90 consists of a cylinder 159 having an aperture 59 and a piston 57 having an aperture 58 arranged to register with the aperture 59 as shown in Fig. 2 upon the return or air intake movement of piston 57. This piston carries a rod 60 to the end of which is 95 mounted a laterally extending arm 61 provided for a purpose that will be hereinafter described in detail.

In the wall of the pressure chamber 54 is 100 mounted a valve OU which consists of a tub-

ing 62 closed at its free end and provided with an aperture 63. Mounted on this tubing is a bell-shaped member 64 arranged to close the opening 63 of tubing 62 under control of piston 57 and a spring 65 is provided to cause the bell-shaped member 64 to follow the movement of arm 61 when this arm is actuated through the movement of piston 57 in turn under control of piston 52, a screw 66 being provided for changing the area of opening 63 for controlling the air pressure in the chamber 54 during the return stroke of piston 52 and thereby preventing the immediate fall of the pressure in the chamber 54 and too great variations in the fluctuation of the gauge.

In a typical example of operation the movement of the operating handle member 26' in a downward direction is effective to actuate the bars 35 and the belt 27-28 carried thereby through the bell crank levers 40 and the supporting plates 19 and 20 through the connecting rods 24. The movement of one of the bell crank levers 40 through its arm 50 is effective to impart movement to the piston 52 from position shown in Fig. 2 to position shown in Fig. 3 for pumping air in chamber 54 against the resistance of the spring 67 holding the ball 68 against the valve seat. The resistance of spring 67 causes the operation of piston 57 position shown in Fig. 2 to position shown in Fig. 3 for closing the opening 59 and simultaneously causes the opening of valve OU which opening is effected through the medium of spring 65 upon the release of the bell-shaped member 64 by arm 61. The continued movement of piston 52 is effective to build up an air pressure in the expansion chamber 54 which pressure is indicated by the gauge 55. But it is to be noted that the opening of outlet 63 is so adjusted as to prevent the building of a too high pressure in the chamber 54 and thus prevents a too great oscillation of the gauge pointer. Upon the beginning of the return or intake movement of piston 52 to normal the spring 67 forces the ball 68 against its seat and the continued movement of this piston is effective to cause a vacuum in the cylinder 53 which vacuum causes the piston 57 to move from position shown in Fig. 3 to position as shown in Fig. 2 wherein the opening 58 of piston 57 registers with opening 59 of cylinder 159 and thus permitting the return stroke of the piston 52 to normal. The downward movement of the piston 57 and the arm 61 carried thereby is effective to operate the bell-shaped member 64 to partially close the opening 63 of the valve OU in order to maintain the air pressure in chamber 54 within a small pressure difference during the return stroke of the handle operating member 26' and the piston 52 connected thereto in order to prevent too violent oscillations of the gauge pointer

which would otherwise occur if this valve remained entirely open during this lapse of time. The flow of air through the opening 63 of valve OU is adjusted through the operation of screw 66 to correspond to a given reading of the gauge and thereby the operation of member 26' and any variation in the operation of the handle member 26' would correspondingly cause different pressure in the expansion chamber 54 which pressure would be indicated by the gauge pointer. Similarly, the uniform movement of the handle operating lever will be effective to maintain the pressure in the pressure chamber 54 substantially constant for any pressure value and this condition will be indicated by the gauge pointer thus giving a positive indication of the movement of the handle operating member.

What is claimed is:

1. In an indicator for a machine for mechanically inducing artificial respiration, said indicator comprising a cylinder, a piston movable in said cylinder and actuated by said machine, an air inlet valve connecting with said cylinder and actuated upon a movement of said piston in said cylinder, a pressure chamber, a valve operable under the action of said piston upon both movements of the latter for admitting and retaining the air in said chamber, a two-way movable valve actuated one way by the first mentioned valve for closing it and the other way automatically for controlling the pressure in said chamber and a gauge for indicating such a pressure.

2. In an indicator, a cylinder, a piston movable in said cylinder, an air inlet valve and an air outlet valve actuated according to the movement of said piston in said cylinder, a pressure chamber connected to the air outlet valve, another valve connected to said chamber, means carried by the air inlet valve for closing the last mentioned valve and automatically operable means for opening it upon a certain operation of said piston in said cylinder for controlling the pressure in said chamber and a gauge connected to said chamber for indicating such a pressure.

In witness whereof, I hereunto subscribe my name, this 5th day of September, 1930.

HOWARD A. FLAMMER.
